UNITED STATES PATENT OFFICE.

ELLA M. MONROE, OF MIDDLETOWN, NEW YORK.

VACUUM GASOLINE FEED.

Application filed April 18, 1922. Serial No. 554,481.

To all whom it may concern:

Be it known that I, ELLA M. MONROE, a citizen of the United States of America, residing at Middletown, in the county of Orange and State of New York, have invented 5 certain new and useful Improvements in Vacuum Gasoline Feeds, of which the following is a specification.

This invention relates to fuel feeding devices for carburetors and, more particularly to fuel feeding devices of the vacuum feed type which may be used to supply fuel from a low level supply tank to a carburetor. The invention, although capable of other uses, is 15 particularly suitable as a fuel feeding means for the carburetors of automobiles and other self propelled vehicles.

The primary object of the invention is to generally simplify and improve devices of 20 this kind whereby the same may meet with all of the requirements for a successful commercial use.

Another object of the invention is to render the various internal parts readily accessible by simple and practical construction and relation of the vacuum chamber and reservoir of the device.

Another object of the invention is to provide a simplified and improved form of float 30 actuated valve mechanism whereby instantaneous and simultaneous closing of the vent port and opening of the suction port is had and vice versa.

Still another object of the invention is to 35 provide an improved and highly efficient means for feeding the fuel to the vacuum chamber and from the vacuum chamber to the reserve chamber or reservoir.

With the above general objects in view 40 and others that will appear as the nature of the invention is better understood, the same consists of the novel form, combination and arrangement of parts hereinafter more fully described, shown in the accompanying drawings and claimed.

In the drawings:

Figure 1 is a view in side elevation, with the walls of the vacuum chamber and reservoir broken away to illustrate internal mechanism of the device constructed in accordance with the present invention.

Figure 2 is a fragmentary elevational view 55 partly broken away looking towards the left of Figure 1 and with the bottom portion of the reserve reservoir removed.

Figure 3 is a top plan view of the device shown in Figure 1 with parts removed and broken away.

Referring more in detail to the several views, the invention embodies a vacuum chamber 5 preferably relatively smaller than the reserve chamber or reservoir 6 and preferably formed integral with the cover 7 of said reservoir 6 so that the chamber 5 will be superimposed upon the chamber 6 when 60 the cover 7 is in place. The cover 7 may be quickly detachable and yet effectively clamped in place by the provision of hinged bolts 8 on the opposite sides of the reservoir 6 adapted for engagement or positioning between 65 pairs of lugs 9 on the cover 7, the upper faces of which are engaged by wing nuts 10 which are threaded upon the bolts 8 for clamping the cover tightly in place. The chamber 5 is preferably provided with 70 a flange 11 at its open upper end to which is suitably bolted a cover plate 12 and the cover 12 is preferably made water tight and air tight by means of a suitable gasket 13 disposed between the cover plate 12 and the 75 flange 11.

The reserve chamber or reservoir 6 is provided with a bottom outlet pipe 14 adapted to communicate with the fuel inlet of a carburetor in the usual manner, and the pipe 80 15 extends axially through the covers 7 and 12 from a point spaced from and above the bottom of the chamber 6 to a point above the cover 12 where it is adapted to be connected with a low level supply tank, not 85 shown. An automatic valve device including a casing 16 is attached to the lower end of the pipe 15 within the reserve chamber 6. said valve device embodying a hollow casing 90 with one port communicating with the pipe 15 and another port communicating with a helical coil pipe 17 which extends from the casing 16 upwardly to a point adjacent the cover 7 where it terminates in an upturned end 18 projecting through the 95 cover 7 into the vacuum chamber 5 near the bottom of the latter. The casing of the valve device 16 has a port at the point denoted by the numeral 19 which is adapted to be closed by suction through the coil 17, 100 by means of a ball or loose valve member 20 arranged within a suitable chamber of the casing 16, and said casing has an additional port 21 opening into the chamber 6 and closed by the ball valve 20 when the lat- 105 110

ter closes the port 19. The ball valve 20 may move away from the port 19 and is limited in such movement by a suitable stop 22, the movement of the valve 20 away from the part 19 providing communication with the chamber 6 from the lower end of the coil 17 through the ports 19 and 21.

The outlet end of a suction pipe 23 is suitably fixed in an opening in the cover 12 of the vacuum chamber 5, and this pipe is adapted to be connected with the inlet manifold of an engine in the usual manner so as to create a suction in the chamber 5 and in this way also create a suction through the coil 17 for drawing the fuel upwardly through said coil from the pipe 15 into the vacuum chamber 5, the fuel being prevented from flowing into the chamber 6 at this time by reason of the fact that ball 20 will be held seated by the suction to cover the ports 19 and 21.

A float 24 is slidably mounted for vertical movement on the pipe 15 within the chamber 5 and is connected by means to be specifically later described so that a vent valve 25, will be opened upon ascent of the float 24 while a valve 26 will be simultaneously closed, the valve 26 controlling the vacuum pipe 23, and such connections also providing for the simultaneous closing of the valve 25 and opening of the valve 26 upon descent of this float 24, such movement of the float being caused by the rise and fall of the liquid fuel in the chamber 5. The valve 25 is the well known atmospheric vent valve and is slidably mounted in a port provided through the cover 12 and includes a stem operatively engaged with a pivoted link 27 which has its inner end mounted as at 28 on a suitable bracket 29 which is fixed on the pipe 15 above the float 24. The link 27 is pivoted as at 30 at its other end to the upper end of a further link 31 which depends and is slidably connected to the float 24 by means of a pin 32 extending through a longitudinal elongated slot 33 provided in the lower end of the link 31, the pin 32 being fixed to the adjacent side of the float 24. The parts having a similar construction and designated by the same numerals, operatively connect the valve 26 with the float 24 at the opposite side of the pipe 15, the only difference in the structure being that the valves 25 and 26 are so proportioned and their seats so arranged that one valve will be opened while the other is closed. For this reason the valve 25 is shown seating downwardly and the valve 26 seating upwardly.

The pin and slot connections 32, 33 between the float 24 and the links 31 is provided for the purpose of giving ample time for the fuel to pass before the valves are tripped. The valves 25 and 26 are adapted to be instantaneously operated and in order

to obtain this result the outer end of one link 27 is connected with the outer end of the other link 27 by means of a pair of transverse tension springs 34 preferably of helical form. Obviously, when the springs 34 pass the pivot points 28 the links 27 will be suddenly and instantaneously swung upwardly or downwardly as the case may be for the operation of the valves. A small vent pipe 35 extends from a point above the maximum level of the gasoline and near the top of the chamber 5 to a point slightly within the upturned end 18 of the coil 17. This vent pipe insures full discharge of the coil 17 before the suction action operates, and thus furnishes a rapidly continuing supply of fuel to the carburetor.

The device is adapted to be fastened upon the dash of an automobile or upon any other suitable support by means of screws or bolts 85 passing through a suitable bracket 36 which is preferably cast integral with the cover 7 of the chamber 6.

In operation, the fuel is first drawn from the gasoline tank through pipe 15 and the coil 17 which is located in the reserve chamber 6 and passes through the coil into the upper chamber or suction chamber 5 as soon as the coil becomes filled. As the fuel comes into the upper chamber it raises the float 24 and this closes the suction valve in the pipe 23 leading to the manifold. At the same time the vent valve 25 is opened and the fuel is discharged into the lower chamber through the coil 17 the weight of the fuel in the coil being sufficient to unseat the valve 20 for this purpose. The fuel may then readily pass from the chamber 6 through pipe 14 to the carburetor. As soon as the coil 17 empties, the float 24 will be lowered and thereby cause closing of the vent valve 25 and opening of the suction valve 26 so that suction again takes place for a repetition of the above operation.

It will be seen, from the foregoing description, that the present device embodies a suction feed for internal combustion engines which will operate perfectly by rapidly created vacuum under the slowest speed as well as under the highest possible speed.

A suitable vent tube 37 communicates with the top of the chamber 6 and preferably extends upwardly alongside the chamber 5, terminating in an inwardly and downwardly turned open upper end portion 38 disposed beneath the flange 11 and constituting a safety vent for the reserve chamber 6.

From the above description of the construction and operation of the device it is believed that the same will be fully understood, it being understood that minor changes are contemplated in details of construction that will fall within the scope of the invention as claimed.

Having thus described my invention what I claim is:

1. A vacuum fuel feed device comprising a reserve chamber or reservoir having a vacuum chamber disposed thereabove, a vertical axial inlet pipe for fuel extending through the vacuum chamber and into said reserve chamber, a helical coil arranged within the reserve chamber and having an open upper end communicating with the bottom of the vacuum chamber, a valve casing secured to the lower end of the fuel inlet pipe and to the lower end of said coil, a suction pipe communicating with the top of the vacuum chamber, and means operable by the suction for causing the fuel to be led from the inlet pipe to said coil, said last named means being operable upon cessation of the suction by the column of fuel in the coil for opening communication between the lower end of the coil and said reserve chamber, and an outlet pipe for said reserve chamber.
  2. A vacuum feed device comprising a reserve chamber or reservoir having a vacuum chamber disposed thereabove, a vertical axial inlet pipe for fuel extending through the vacuum chamber and into said reserve chamber, a helical coil arranged within the reserve chamber and having an open upper end communicating with the bottom of the vacuum chamber, a valve casing secured to the lower end of the fuel inlet pipe and to the lower end of said coil, a suction pipe communicating with the top of the vacuum chamber, and means operable by the suction for causing the fuel to be led from the inlet pipe to said coil, said last named means being operable upon cessation of the suction by the column of fuel in the coil for opening communication between the lower end of the coil and said reserve chamber, an outlet pipe for said reserve chamber, and a vent pipe extending in the vacuum chamber from a point near the top of the latter slightly into the upper end of said coil.
  3. A vacuum fuel feed device comprising a reserve chamber or reservoir having a vacuum chamber disposed thereabove, a vertical axial inlet pipe for fuel extending through the vacuum chamber and into said reserve chamber, a helical coil arranged within the reserve chamber and having an open upper end communicating with the bottom of the vacuum chamber, a valve casing secured to the lower end of the fuel inlet pipe and to the lower end of said coil, a suction pipe communicating with the top of the vacuum chamber, means operable by the suction for causing the fuel to be led from the inlet pipe to said coil, said last named means being operable upon cessation of the suction by the column of fuel in the coil for opening communication between the lower end of the coil and said reserve chamber, an outlet pipe for said reserve chamber, and a vent pipe extending in the vacuum chamber from a point near the top of the latter slightly into the upper end of said coil.

- opening communication between the lower end of the coil and said reserve chamber, an outlet pipe for said reserve chamber, said valve casing having a lateral port and a valve chamber, and a loose valve within this valve chamber operable by the suction for closing said port.
4. A device like that described in claim 1 wherein the vacuum chamber is provided with an atmospheric vent port, a valve normally closing said port, a second valve normally allowing communication between the vacuum chamber and the vacuum pipe, a float slideable on the fuel inlet pipe in a vertical direction, and means operatively connecting said float with said valves whereby the vent valve is opened upon ascension of the float while simultaneous closing of the suction pipe valve is had instantaneously.
5. A device like that described in claim 1 wherein the vacuum chamber is provided with an atmospheric vent port, a valve normally closing said port, a second valve normally allowing communication between the vacuum chamber and the vacuum pipe, a float slideable on the fuel inlet pipe in vertical direction and means operatively connecting said float with said valves whereby the vent valve is opened upon ascension of the float while simultaneous closing of the suction pipe valve is had instantaneously, said operative connections between the float and the valve embodying a link pivoted to a fixed portion of the inlet pipe above the float, a second link pivoted to the other end of the first named link and longitudinally slidably attached to said float, and tension means operatively connecting the links of each valve at the pivotal connection between said links of each valve.
6. In a vacuum feed device, a lower reserve chamber having a bolted on cover with an integral vacuum chamber, means operable by suction for feeding fuel to the suction chamber and upon cessation of suction to allow said fuel to flow to the reserve chamber, said last named means including an inlet fuel pipe, a coil arranged within the reserve chamber and communicating with the fuel inlet pipe and vacuum chamber, and means operatively connecting the fuel inlet pipe with the coil for automatically causing the fuel to flow to the vacuum chamber through the coil from the fuel inlet pipe upon occurrence of suction in the vacuum chamber and movable by the liquid in the coil and vacuum chamber for allowing said fuel to pass through the coil to the said reserve chamber, upon cessation of the suction.

In testimony whereof I affix my signature.

ELLA M. MONROE
